US00D554086S

(12) **United States Design Patent** (10) **Patent No.:** **US D554,086 S**
Hsiung (45) **Date of Patent:** **** Oct. 30, 2007**

(54) **PORTABLE DVD PLAYER**

(75) Inventor: **Chen Kuo Hsiung**, Laguna (HK)

(73) Assignee: **Silicon Pyramid Electron**, Kowloon (HK)

(**) Term: **14 Years**

(21) Appl. No.: **29/237,412**

(22) Filed: **Aug. 31, 2005**

(30) **Foreign Application Priority Data**

May 27, 2005 (CN) 2005 3 0060097

(51) **LOC (8) Cl.** **14-03**

(52) **U.S. Cl.** **D14/129; D14/132**

(58) **Field of Classification Search** D14/125, D14/129, 132, 136, 156, 374, 375; 348/180, 348/184, 325, 838; 341/12; 345/104, 133, 345/156, 168, 173, 87; 720/605, 669, 600, 720/655; 369/99, 197; 455/344, 345, 346, 455/347, 566; 368/12

See application file for complete search history.
